UNITED STATES PATENT OFFICE.

MARTIN D. GARNER, OF TULSA, OKLAHOMA.

TELEPHONE EQUIPMENT.

Application filed August 31, 1925. Serial No. 53,713.

The invention has for an object to present an improvement in equipment for telephone booths and elsewhere, to facilitate the utilization of the telephone. It is a special purpose to offer new devices to automatically close circuits suitable for lighting and indicating occupancy of booths, and also to provide for special illumination when required, as for writing; while at the same time insuring proper setting of circuits in initial positions when a booth is vacated. It is also an aim to add conveniences to telephone supports for the benefit of users generally in various situations.

It is a specific object to embody a novel and desirable form of mechanism actuated by movement of the receiver hook to control lighting circuits, and which will provide for movement of the receiver hook without disturbing these circuits if necessary as, when it is required to attract attention of a telephone central operator by producing signal impulses in the telephone circuit. A further object is to provide a novel device cooperatively associated with the last mentioned apparatus and circuits whereby departure of a patron from the telephone will place the circuits in initial condition, so as to remain independently of any further movements of the door, until a patron again desires to make use of the equipment.

Additional objects, advantages and features of invention reside in the specific construction, the combination and the arrangement of parts, as will be more readily understood from the following description and accompanying drawings of one embodiment of the invention, wherein,

Figure 1 is a top view of a telephone installation in accordance with my invention.

Figure 2 is a front elevation thereof.

Figure 3 is an elevational detail of a receiver hook switch and operating mechanism.

Figure 4 is a detail diagram of door connections with the manual switches.

Figure 5 is a wiring diagram of the equipment.

Figure 6 is a diagrammatic illustration of a telephone installation with one type of booth.

Fig. 7 is an elevation of a closed booth.

There is illustrated a table element 10, which may be a shelf or the top of any structure of suitable height. It is formed with a central opening 11 over which there is set

the base 12 of the usual telephone transmitter 13, which includes the mouthpiece 14 and vertically oscillatable, resiliently supported, receiver hook or telephone switch 15. A 60 telephonic receiver 16 is also illustrated, of a familiar type such as is ordinarily held to the ear by one hand and this is hung in the usual way on the hook 15 when the telephone is not in use. The specific details of the telephone circuits and switch may be of the common form and comprise no novel part of this invention. The base of the transmitter is secured to the table 10 by a collar 17.

65 A writing shelf 18 and book rack 19 are 70 shown. On a standard 20 there is an electric lamp 21, adapted to throw suitable illumination upon the book rack, and transmitter, while on a similar standard 22 there is a light 23 arranged to illuminate the writing 75 shelf. Mounted on the rack 19 there is similarly extended a flexible arm 26, means 27 being provided to secure it in extended positions.

Pivoted on the arm 26 at its extremity 80 with a ball and socket joint 28 there is a second rigid arm 29; the ball and socket joint being of a type including a clamping screw 30 by means of which the arm 29 may be universally adjusted and secured at various 85 positions on its pivot. At the outer end of the arm 29 there are two furcations 31 the outer parts of which are bowed downwardly as at 32 forming together a rest in which the receiver 16 may be laid. Medially between 90 and above the furcations there is a resilient retainer spring 33 having a shape similar to that of the furcations 31. The extremities of the furcations and spring are divergent so that a receiver may be laid against these 95 divergent parts and by pressure at the outer side forced between the spring and the furcations. If desired, the arm 29 may be longitudinally extensible.

Rearwardly of the receiver 13 there is a 100 switch panel 32, upon which there is mounted a simple switch 33 including a pivot arm 34 operable by vertical movement, a link 35 being connected thereto extending downwardly to the intermediate part of the 105 hook arm 15, to which it is pivotally connected so that the switch will be operated by movement of the hook 15. The switch includes upper and lower contacts 36-37, and serves to close on the lower contact a 110 circuit 38 to a white light 39 at a distant point to indicate that the telephone is not

in use, while on the upper contact it closes a circuit 40 to a red light 41 in the same situation and also the white light 21 before mentioned on the standard 20.

5 On the panel 32 there are also located wall switches 42 and 43, one adapted to close a circuit 44 to the lights 41 and 21 as mentioned and the other adapted to close a circuit 45 to the light 23 before mentioned for 10 illuminating the writing shelf, as indicated in the diagram in Figure 5, wherein a battery 46 is formally indicated as the source for energizing the circuits.

The switches 42-43 are of the familiar snap, lever, type, and means is provided to insure extinguishing of the lights 21-23-41 when a patron leaves a telephone booth or leaves the telephone. It is considered undesirable merely to break the circuits to 20 the lights independently of the switches 42-43 which would impair the utility of these devices, and therefore the means is of a character to return these switches to initial "off" position.

25 Each of the levers 50 of the switches 42-43 have connected thereto draft links 51 extending backwardly from the switch and attached to the ends which are to be moved inward to off position, and at suitable distance an equalizer bar 52 is connected across these links. From the middle of the bar a draft connection 53 including a slightly resilient element 54 is extended to a lever 55 located adjacent the door or other hinged 30 element 56 by which patrons gain access to the telephone. This element 56 has a wiper 57 having a dog 58 on the end adapted to yield to the lever 55 when the element 56 is moved to closed position, and upon movement of the element 56 to open position will 35 positively engage and move the lever 55 so as to move it for resetting of the switches 42-43, as may be understood. In case the switches are already in initial or off position the lever 55 will not be operated but will be then held in operated position by the 40 switches 40-41 unless some alternative connections are employed.

Pivoted on the panel 32 also there is a 45 means to operate the hook 15 without disturbing the light circuits in case it is desired to attract the attention of a central operator. This consists of a hand lever 60 pivoted intermediately of its length with a 50 lower end disposed conveniently to be grasped together with the column of the transmitter 13 so that by tightening the grip upon the two the lever will be operated, the transmitter serving to give the patron a 55 purchase by which the lever may be operated with a minimum effort. A spring 61 is provided to hold the lever yieldingly in initial position.

60 A second lever or switch arm 62 is pivoted at one end on the panel 32 having an

initial operative position with its opposite or swinging end extended upwardly a little toward the transmitter or lever 60. Stops 63 are provided to limit movement of the arm 62, and a contact 64 is located to be 70 engaged by the arm when operated from initial position, to close a circuit to the lights 41 and 21. A link 65 is connected to the upper end of the lever 60 and mutually pivoted on the inner ends of toggle links 75 66 the outer end of one of which is connected to the upper end of the switch arm 62 and the outer end of the other connected to the outer part of the hook 15. The parts are so arranged relatively that when the 80 switch arm 62 is in operated position through operation of the hand lever 60, the links 66 are extended in an oblique relation between the hook 15 and the arm 62, and when the lever 60 is released it operates 85 through the link 65 to draw the levers 66 toward the right first permitting the hook to rise, and then drawing the arm 62 to initial or open circuit position against the 90 stop.

95 It will be seen that in the use of my appliance a patron may ascertain from a distance whether any one else is using the phone or is in the booth therewith, by reason of the illumination of the red light displayed, and if the phone is not engaged by any one a white light will be displayed. This is especially useful in large public stations where banks of booths are provided, and is also desirable even when but a single phone 100 installation is provided, to avoid awkward situations between patrons.

When the receiver is removed from the hook the movement of the latter will automatically change the distant signal from 105 white to red at the same time that the interior of the booth is illuminated, or, if the patron desires first to search a name in the directory he will press a button of a wall switch provided for the purpose, which will cause display of the red distant signal and illuminate the booth by the same lights involved in operation of the hook 15.

110 It is an advantage of my appliance that in case any one operates the door or other device 56 while a patron is using the telephone it will not extinguish the distant signal nor the booth illumination but will leave these in a condition to be automatically restored to initial condition when the receiver is 115 hung up.

120 It will be seen that the appliances involved are of a simple character adapted to be produced readily at a low cost, and that they are of a durable character and liable in a 125 minimum degree to derangement; as well as being applicable to many various types of installations. As indicated in Figure 6, in case the telephone is not enclosed in a booth, a chair 70 may be provided with a swing- 130

ing arm 56' which will require to be operated by a patron in leaving the seat, which will insure the functions of restoring circuits to initial position after manipulation of the switches.

The hook 15 is broadly reciprocatable in its oscillatory movement, and in claim 4 the "reciprocatable member" is supported in this disclosure by the hook 15.

10 I claim:

1. In telephone equipment, a telephone circuit switch, a light circuit controlled thereby, a manually operable switch to control the light circuit, a booth closure and means operatively associated therewith to reset the last named switch in initial position when said closure is opened.

2. In telephone equipment, a telephone circuit switch, a light circuit controlled thereby, a second light circuit, a manually operable switch to control the light circuits, a booth closure and means operatively associated therewith to reset the last named switch in initial position when said closure is opened.

25 3. In telephone equipment, a telephone

circuit switch, a light circuit switch connected positively therewith, a third switch and operating means therefor having a lost motion connection with the telephone circuit switch, and a light circuit controlled by the second and third named switches.

4. The combination of a reciprocatable member, a light circuit, a switch therefor, operative connections between the reciprocatable member and the switch, a second switch connected to separately close the light circuit at times when the first named switch is open with respect to said circuit, a lever operatively connected with the second switch and operative connections between the lever and reciprocatable member constructed to close the second switch during movement of the reciprocatable member over a predetermined part of its path.

5. The structure of claim 4 in which the first named switch is operatively associated with a second light circuit in a relation to close the same when the switch is in open relation to the first named light circuit.

In testimony whereof I affix my signature.

MARTIN D. GARNER.
